UNITED STATES PATENT OFFICE.

TANDY A. BRYSON, OF TROY, NEW YORK, ASSIGNEE TO TOLHURST MACHINE WORKS,
A CORPORATION OF NEW YORK.

CENTRIFUGAL PROCESS.

1,280,153.

Specification of Letters Patent.

Patented Oct. 1, 1918.

Original application filed November 28, 1914, Serial No. 874,487. Divided and this application filed March 21, 1918. Serial No. 223,760.

To all whom it may concern:

Be it known that I, TANDY A. BRYSON, a citizen of the United States, and a resident of Troy, New York, have invented new and useful Improvements in Centrifugal Processes, of which the following is a specification.

The invention relates to a process for centrifugally extracting water or other moisture from dense, or finely divided, or minutely comminuted materials, such for instance as clays, linseed oil foods, apple skins, and other substances, which under centrifugal action pass into a dense or impervious layer; this application being a division of my application Ser. No. 874,487, filed November 28, 1914.

The objects and advantages of the invention will be set forth in part hereinafter, and in part will be obvious herefrom, or may be learned by practice with the invention.

The accompanying drawings, referred to herein and constituting a part hereof, illustrate in part the invention, and together with the description serve to explain the principles thereof.

Of the drawings:

Figure 1 is a vertical section on the line 30 A—B of Fig. 2; and

Fig. 2 is a full horizontal section on line C—D of Fig. 1.

In the usual manner of filtering or dewatering most materials by centrifugal action, a filtering medium or instrumentality is placed at the peripheral walls of the cylindrical container. When two or more materials of different specific gravity are centrifuged, the heavier material, usually a solid, will take its position in a layer upon the vertical peripheral wall of the container and the lighter material, usually a liquid, will take its position in a layer within, such outer and relatively dense layer.

The drying or dewatering in such cases is effected by depending on the lighter liquid to find its way in a substantially radial direction through the minute interstices of the heavier material and out through the walls 50 of the container. When the heavier material is relatively dense or minutely divided or comminuted, the lighter liquid within is hindered or entirely prevented from so pass-

ing out. A very thin layer of dense or finely divided material, such as clay, is sufficient to clog the filter, thus stopping the process and retaining a layer of liquid on the inner surface of such impervious wall. The dewatering is thus prevented or rendered economically inefficient.

By my invention the impervious layer of clay, or other finely divided or otherwise impervious materials, is allowed to build up in thickness about the periphery, and a continuous drainage of the separated liquid layer from the interior surface of the gradually thickening and building layer of solid material is maintained, the drainage being maintained in uniform and constant relation to the inner surface of the layer notwithstanding its increase in thickness and consequent change in position. My invention provides also for a continuous straining or filtering of the intermediate stratum or layer which is in intermediate state or condition between the liquid and the solid layers, and which is partly dewatered, and thereby is somewhat condensed, but which is not yet closely compacted into the condition of the dense and impervious outer layer, this action being maintained likewise irrespective of the gradual change in the thickness of the peripheral layer.

By one feature of my invention also, means are provided for removing the relatively slight amount of retained moisture which can be drained from the outer layer of solid material, if permitted to do so, by the pressure of the centrifugal action, as the compacting action or operation passes into its final stages.

By my invention, the filtering surface or moisture tapping device is positioned or extended in a general radial direction beyond or within the layer of denser and heavier material in the centrifugal machine to bring such surface or device into direct communication with the inner layer of liquid, and this liquid may then be carried or flowed away without passing through the outer and denser layer. By the action of centrifugal force, the inner wall or surface of the dense outer material will be in effect a level surface, and the liquid will be free to flow over it in a circumferential direction to an unobstructed outlet. Thus the material is quickly

dewatered and the work is performed quickly, thoroughly and efficiently from an economic or commercial standpoint.

In the embodied form of mechanism, and referring to Fig. 2, a bowl or container 1 has vertical cylindrical side walls 2 and a bottom 3, and is preferably partly open at the top having an inwardly extending ring or annular plate and also may have a suitable closure if desired. The shaft for rotating the basket or container passes through the opening 5. The invention is herein applied to an intermittently operated centrifugal, that is, one which is stopped to unload and load, although in certain of its features the invention is applicable to other kinds of machines. In the embodied form, the interior is largely unobstructed affording great facility for loading and unloading.

A tapping or filtering device for flowing off the inner liquid layer, as already described, is provided. In the embodied form thereof, a vertically arranged wall 8 is fixed to the wall 2 of the bowl or container and is angled or returned back again to the wall 2, being preferably of V shape in horizontal section with the upper ends joining the periphery of the basket or container. There are preferably a plurality of the tapping or filtering devices 8, and they may be bolted or otherwise suitably fastened to the wall 2. Wall 8 is provided with openings for the filtering or passing through of the liquid. As embodied there are perforations 9 in the wall 8, and over the wall 8 is stretched or spread a sheet or layer 10 of wire gauze or other suitable foraminous material. The liquid is carried off from the other side of wall 8 by suitable means and for this purpose the wall 2 is preferably made perforate where inclosed by 8, as shown at 11. The liquid will thus flow in a circumferential direction through the openings in 8 and will then be thrown out by centrifugal action through the openings at 11.

It will thus be seen, as previously indicated, that the inner layer of liquid will be drained off and that there is a concurrent filtering, through the gauze 11, of the partly deliquidized, and thereby partly condensed or compacted material which exists intermediate or between the separated liquid at the interior and the impervious layer at the exterior, and that these two operations will continue unimpeded as the layer of compacted material builds up or becomes thicker as the process proceeds. That is, there is maintained a combined drainage of the clear liquid and a filtering or straining of the intermediate mixed liquid continuously from just within the impervious layer as that layer builds up. The conditions of deliquidizing are thus maintained in a constant or uniformly efficient state throughout the changing operation, producing a uniformly and

substantially entirely dried mass as the final result of the process.

The operation will continue, as indicated, until the entire mass is entirely deliquidized and compacted, and there will not be a residue of sludge or partly deliquidized material at the end of the operation.

While the outer layer is impervious to the passage of liquid therethrough, there is a very slight amount of moisture left between the particles of the relatively solid or compacted mass, and this as it is further subjected to the pressure of the centrifugal action is drained off through the outlets of the members 8, and as this drainage proceeds this final degree of moisture is gradually gotten rid of, leaving a compact and uniformly dry mass in the centrifugal.

In addition to the improved and advantageous way of treating the material and effecting the drying or dewatering, the mechanism is of simple form and requires no general changes in the usual form of centrifugal basket or container. It may also be easily and quickly applied to and removed from existing baskets, thus permitting the use of a single basket or container for different kinds of work and materials. Where the walls of a basket or container are perforate, the wall 2 may be an inserted thin inner wall of sheet metal. The mechanism is simple and inexpensive, and the greater part of the interior of the basket is left unobstructed for loading and unloading and for cleaning.

The invention in its broader aspects is not limited to the precise form shown and described, but variations may be made therein without departing from the principles of the invention and without sacrificing its chief advantages.

What I claim is:—

1. The process of centrifugal deliquidizing which comprises subjecting to centrifugal action a mixture of finely divided impervious material in suspension in a liquid and thereby forming and retaining a gradually thickening outer layer of the impervious material separated out of the solution and simultaneously draining off the separated liquid from just within the impervious layer and so maintaining said drainage continuously from just within said outer layer as it builds up, and continuing said actions until substantially all the liquid and solid are separated from each other.

2. The process of centrifugal deliquidizing which comprises subjecting to centrifugal action a mixture of finely divided impervious material in suspension in a liquid and thereby forming and retaining a gradually thickening outer layer of the impervious material separated out of the solution and simultaneously draining off the separated liquid from just within the imper-

vious layer and so maintaining said drainage continuously from just within said outer layer as it builds up, and simultaneously and continuously filtering off liquid from the partly deliquidized and thereby partly condensed mixture which is intermediate the impervious outer layer and the inner liquid layer.

3. The process of centrifugal deliquidizing which comprises subjecting to centrifugal action a mixture of finely divided impervious material in suspension in a liquid and thereby forming and retaining a gradually thickening outer layer of the impervious material separated out of the solution and simultaneously draining off the separated liquid from just within the impervious layer and so maintaining said drainage continuously from just within said outer layer as it builds up, and simultaneously draining the slight residual moisture from the impervious layer by the centrifugal pressure.

4. The process of centrifugal separation which comprises subjecting a mixture of finely divided insoluble and impervious material in suspension in a liquid to centrif-

ugal action and thereby gradually building up an outer layer of the separated impervious material and continuously maintaining a combined drainage of the clear liquid and a straining of the mixed and partly condensed liquid and solid from just within and in continuing uniform relation to the impervious layer as that layer builds up.

5. The process of centrifugal deliquidizing which comprises subjecting a mixture of finely divided impervious material in suspension in a liquid and thereby forming and retaining a gradually thickening cylindrical outer layer of the impervious material separated out of the solution and simultaneously draining off the separated liquid from just within and substantially along the entire length of the impervious outer cylindrical layer as it builds up.

In testimony whereof, I have signed my name to this specification, in the presence of two subscribing witnesses.

TANDY A. BRYSON.
